UNITED STATES PATENT OFFICE

ALEXANDER E. LATCHIN, OF CHICAGO, ILLINOIS

ARTICLE SHELF

Application filed April 9, 1929, Serial No. 353,775. Renewed June 6, 1932.

My invention relates to shelves for the support of portable articles, and more particularly for the support and display of an alarm clock in the home and my main object is 5 to provide a device of this kind which is peculiarly formed to dispose the clock in proper position and in prominent view.

A further object of the invention is to incorporate in the shelf a lamp to illuminate 10 the face of the clock.

A still further object of the invention is to provide a novel method of suspending the shelf from a wall.

Another object of the invention is to incorporate in the same means for mounting 15 and clamping it upon the rail of a bedstead.

A final but nevertheless important object 20 of the invention is to design the novel invention with few and simple parts, in order that it may be easy to handle and inexpensive to produce.

With the above objects in view and any 25 others that may suggest themselves from the specification and claims to follow, a better understanding of the invention may be gained by reference to the accompanying drawing, in which—

Figure 1 is an elevation of the novel shelf, showing the clock mounted therein;

Fig. 2 is a section on the line 2—2 of Figure 30 1, and partly broken away;

Fig. 3 is a side view of the shelf as mounted on a bedstead; and

Fig. 4 is a plan view of a shelf as per Figure 35 3, partly in section.

Referring specifically to the drawing, the fundamental support for the shelf is in the nature of a base plate 10, which is made with 40 a marginal wall 10a from which outward flanges 10b extend. The plate is set up against a wall as shown in Figure 2, with the flanges 10b abutting the wall, so that the body of the plate is spaced from the wall.

45 The plate is secured by screws 11 or other suitable means applied by way of the flanges 10b to the wall.

The plate 10 is provided with angle brackets 12, secured to the plate by screws 13, the 50 top portions of the brackets also being aper-

tured to receive screws, as will later be explained.

The brackets 12 are designed to receive in superposed relation, the bottom 14 of the shelf. At the rear, this bottom is built up 55 with a guard strip 15 and in front it is built up with a wall 16 having sides 16a. The wall 16 is cut down from the top with an arcuate recess 16b, so that when a typical alarm clock 17 is set upon the floor 14 of the shelf, the dial will be defined at the bottom by the wall 16 and be fully visible while the bottom of the clock is securely held within the shelf. The front wall 16 also has a skirt portion 18.

In order that the shelf may be in a position to swing laterally whereby to expose the face of the clock in a corresponding direction, I secure by means of bolts and nuts at 19 a U-shaped bracket 20 which is passed through a 70 vertical mounting 21 on the side of the shelf wall 16a in order to hingedly dispose the shelf. Since the bolt and nut assembly 19 requires four holes in the plate 10, as indicated in Figure 1, it is of advantage to also drill four holes of similar size and spacing at the remote side of the plate as indicated at 19a, so that in case the shelf is desired to be swung in the opposite direction, such as 75 where the clock has to be viewed from the corresponding side, the mounting and the other parts incident to the hinge may be removed from the side shown and transferred to the opposite side of the shelf to enable the same to swing as contemplated.

When the shelf is set in place upon the brackets 12, transverse slots 16c in the floor of the shelf register with the apertures in the top portions of the brackets 13a, making it feasible to apply screws by way of the slots and the apertures in the top portions of the brackets, as indicated by the showing in Figure 4, to receive nuts from below in order to fasten the shelf to the brackets 12 and therefore lock the shelf from swinging out 95 accidentally.

The floor 14 of the shelf is made with two openings 16d, extremely spaced, these being suitable for the passage of cords 22 from the alarm control 23 of the clock, the cords ex- 100

tending in opposite directions from the latter. Thus, when one of the cords is pulled down, the alarm is set, and when the other is pulled after the alarm is in operation, the alarm is shut off. The cords preferably have ball ends 24 at the bottom for facility in handling them as mentioned.

The above installation of the shelf is preferable on a wall adjoining one's bed, and is designed for use when the bed cannot form the fundamental support for the device. Figures 3 and 4, however, illustrate the application of the shelf to a bedstead having a round top bar 25. In this case, the shelf is set upon the top bar 25 with the skirt 18 to the front, an angle clamp 26 being applied at the rear to fasten the shelf to the bar. The top portion of the angle clamp extends under the slots 16c of the shelf floor, and is slotted in registration with the said slots, so as to permit fastening by bolts 27 secured by nuts 27a in any position of adjustment toward or from the bar 25. To secure the clamp 26 to the bedstead, I apply a thumb screw 28 by way of the pendant portion of the clamp, locking the thumb screw by means of nuts 29 after it has been advanced to secure a firm grip on the bar 25.

The front wall 16 of the shelf is made with a knob 16e for handling purposes when the shelf is to be swung out; also, the said wall is provided with a lamp fixture 30 shaped to cast light downwardly upon the face of the clock, the fixture having a suitable cord connection extending to a handy current outlet, and also a suitable push button control.

It will be seen that the novel shelf is susceptible of being positioned both against the wall and upon a bedstead. When positioned against the wall, most of its connections do not affect the wall, only the few screws used for the attachment of the base plate 10 passing into the wall. The shelf is useful both frontally of the wall and in either lateral direction if the position from which the clock is viewed is at one side or the other. The attachment of the shelf to the bedstead only requires the removal of the bolts securing the same to the brackets 13a and to the base plate 10, the shelf then being transferred and mounted as shown in Figures 3 and 4. A handy device is thus had for viewing the time from one's bed or from a position which is not convenient relative to the conventional wall clock.

I claim:—

1. An article shelf comprising a wall plate, a support in front of the same, and hinge means applicable selectively between the sides of the support and the plate for the swinging of the support relative to the wall from the corresponding side of the support.
2. An article shelf comprising a wall bracket, a support comprising a plate, side and rear guards and a front wall for the plate,

and a hinged connection located on each of the side guards for selectively securing the support to the bracket.

3. An article shelf comprising a wall bracket, angle members secured thereto, a support hingedly connected to the bracket, and cooperating means on the support and the angle members to free the support for movement to its hingedly adjustable positions relative to the bracket. 75

4. An article shelf comprising a wall bracket, angle members secured thereto, a support hingedly connected to the bracket, a bottom plate for the support, and cooperating means on the bottom plate and angle members to free the support for movement to a desired position on its hinge. 80

5. An article shelf comprising a wall bracket, a support having side guards, a tubular member secured to a guard, and a U-shaped hinge rod embraced by the member, said rod attached to the bracket. 85

6. An article shelf comprising a wall bracket, a support characterized by a bottom plate, side and rear guards and a front wall 90 for the plate, means on each of the side guards for selectively and hingedly securing the support to the bracket and means carried by the bracket and operatively associated with the bottom plate to free the support for movement to its various positions when swung about the hinged connection. 95

In testimony whereof I affix my signature.

ALEXANDER E. LATCHIN.
